UNITED STATES PATENT OFFICE.

FRANK J. VARNUSKA, OF NEW YORK, N. Y.

TOY HOUSE.

1,425,425.

Specification of Letters Patent. Patented Aug. 8, 1922.

Application filed August 31, 1921. Serial No. 497,151.

To all whom it may concern:

Be it known that I, FRANK J. VARNUSKA, a citizen of the United States, and a resident of the city of New York, borough of Manhattan, in the county and State of New York, have invented a new and Improved Toy House, of which the following is a full, clear, and exact description.

This invention relates to new and useful 10 improvements in toys, and it pertains more particularly to a toy in the form of a building adapted to be knocked down and reconstructed.

It is one of the objects of the invention to 15 provide a toy building which can readily be assembled and disassembled.

It is a further object of the invention to provide doors and windows for the toy house of such a character that they may be placed 20 upon any side of the house.

It is a further object of the invention to construct the side walls of the house in such a manner that the doors and windows may be positioned in any of the sides and the 25 side walls completed therearound.

It is a further object of the invention to paint the material forming the side walls of different colors on their opposite sides in order that a completed house of one color 30 or another may be formed.

It is a still further object of the invention to provide a roof and to construct the building in such a manner that it is square, thus adapting the roof to use in any position on 35 the house as desired.

With the above and other objects in view, reference is had to the accompanying drawings, in which—

Figure 1 is a perspective view of a toy 40 house constructed in one of its forms;

Fig. 2 is a top plan view of the base of said house;

Figs. 3, 4, 5, and 6 are views in elevation of the various sides of the house and the 45 different forms in which they are constructed;

Fig. 7 is a transverse sectional view taken on the line 7—7 of Fig. 1;

Fig. 8 is a vertical sectional view taken 50 on the line 8—8 of Fig. 1;

Fig. 9 is a horizontal sectional view taken on the line 9—9 of Fig. 1;

Fig. 10 is a detail top plan view of one of the corner posts showing its construction

and the manner in which the corner posts 55 and stringers are connected together;

Fig. 11 is a vertical sectional view taken on the line 11—11 of Fig. 10;

Fig. 12 is a detail view of the several forms of siding or side boards used. 60

Referring more particularly to the drawings, the reference character 15 designates a base which may be formed of wood or other suitable material. The base 15 is provided with a plurality of recesses 16 extending 65 around the same near the edge thereof, said recesses being arranged in predetermined spaced relation one to the other. The reference character 17 designates vertical corner posts and each of said vertical corner posts 70

is provided with a reduced extension 18 adapted to be received in the corner recesses 16 of the base 15. These vertical corner posts 17 are preferably rectangular in form 75 and are provided on two of their adjacent faces with grooves or the like 19. These corner posts 17 are further provided in their upper ends with recesses 20 and a portion of the wall separating the recesses 20 and

each of the grooves 19, is cut out as indicated by the reference character 21. In the form of the house shown there are four of these corner posts 17 used, and they are so positioned that their grooved faces will be 80 in alinement with the several recesses 16 in 85 the base 15.

Connecting the upper ends of the vertical corner posts 17 are stringers 22, and said stringers 22 are provided with hooked metallic members 23 adapted to be received with 90 in the slots 21 and the recesses 20 of the vertical corner posts 17.

The reference character 24 designates door sections, and 25 designates window sections, and each of these door and window sections 95 is constructed in the form of a frame, the door section 24 being provided with reduced portions similar to the reduced portions 18 of the corner posts and adapted to be received within certain of the recesses 16 in 100 the base 15. The window sections are rectangular, the outer edges of which are grooved as indicated by the reference character 26 in Fig. 9, and said window sections are adapted to be positioned in the walls of 105 the house in a manner to be hereinafter more specifically described.

The side walls of the house are construct-

ed of sections of boards of various lengths, the several sections of siding being designated by the reference character 30 and the relative lengths of said sections being shown 5 in Fig. 12.

The roof 31 comprises two members 32 and 33 secured together by means of a hinge 34, said member 32 having permanently secured thereto a ridge pole 35. This ridge 10 pole 35 is substantially triangular in cross sectional form and has one of its sides overlapping the member 33 as indicated by the reference character 36 in Fig. 7.

Sections of siding 37 are employed to 15 close the space between the horizontal stringers 22 and the ridge of the roof, as more clearly shown in Fig. 1, and said sections 37 are secured in position by means of pins 38 carried thereby adapted to be 20 received in recesses 39 suitably positioned in the horizontal stringers 22.

The house or building is assembled in the following manner: The base is first positioned, after which the vertical corner posts 25 17 are secured in the corner recesses 16 of said base. After this has been accomplished, the sections 30 of siding are positioned in the grooves 19 of the corner posts and the window and door sections 24 and 25, respectively, are positioned in any desired arrangement, the various lengths of siding sections 30 permitting of this various positioning of the doors and windows being carried out. After the several door and window sections 35 have been positioned, as desired, the longitudinal stringers 22 heretofore mentioned engage in the recesses 20 and slots 21 in the upper end of the vertical corner posts 17. After this has been done, the sections 37 40 are positioned in the manner heretofore described, and the roof placed upon the house, thus presenting a complete structure.

From the foregoing it is apparent that the present invention provides a toy house which 45 may be readily assembled and knocked down, and that owing to the peculiar con-

struction of the members which form the side walls of the house, which permits of the placement at will of the door and window sections, an unlimited range of house 50 design is had.

In carrying out the invention the several side members 30 are painted upon one of their sides in one color and upon their other side in a different color. By means of this 55 construction, it is apparent that houses of different colors may be constructed by a mere reversal of the side members 30.

From the foregoing it is apparent that the present invention provides a new and 60 novel form of toy, the use of which is very entertaining and provides an instructive pastime owing to the variations which may be resorted to in the construction of a house with the several elements disclosed herein. 65

I claim:

1. A toy building comprising a base, vertical posts carried by said base, side walls for the building formed of side members of various lengths, door and window sections 70 adapted to be positioned in the side walls of the building, stringers connecting the upper ends of the vertical posts of the building and a roof for said building, said roof comprising two members hingedly secured together on their inner face, and a ridge pole rigidly carried by said members and overlapping the joint between said members, substantially as described.

2. A toy building comprising a base, a 80 plurality of vertical posts adapted to be adjustably secured with respect to said base, side walls formed of individual board sections adapted for interengagement with the posts, stringers connecting the upper ends 85 of the posts and forming a portion of the side walls of the building, and a roof comprising hinged sections adapted to be supported by the side walls of the building, substantially as described.

FRANK J. VARNUSKA.
